ELECTRONIC COMPUTER

Arthur W. Vance, Moorestown, N. J., assignor to
 Radio Corporation of America, a corporation
 of Delaware

Application August 29, 1942, Serial No. 456,591

6 Claims. (Cl. 235—61.5)

1

This invention relates generally to electronic computers, and particularly to apparatus for deriving the value of a predetermined function of a selected quantity which is applied to the computer as a voltage proportional in amplitude to the value of the original quantity.

Heretofore, various devices have been disclosed for deriving predetermined functions of quantities applied as driving voltages. Many such systems utilize the scanning action of light beams or cathode rays across especially constructed screens having predetermined fiducial markings.

The instant system utilizes the adjustable non-linearity of resistance of a network which includes a non-linear resistance element such as Thyrite. By a suitable combination of linear resistive elements with such non-linear resistive elements, a voltage applied to the network may provide an output voltage the value of which is a complex function of the input voltage.

For example, it has been found that a Thyrite element combined with a parallel linear resistor and a series linear resistor of predetermined relative values may be made to provide an output voltage directly proportional to the time of flight when a voltage of magnitude proportional to the value of slant range in a ballistics equation is applied to the network.

The characteristics of Thyrite are described in General Electric Review for April 1934, pages 175-179 and May 1934, pages 218-223 inclusive. The characteristics of particular pieces of Thyrite vary considerably with size, shape, applied voltage and molecular composition. In general, a particular Thyrite element has a characteristic represented by the formula $I=KE^v$, where K and v represent characteristics peculiar to the individual Thyrite element. Since the resistance of a network including a Thyrite element is a function of input voltage, best results are obtained with applied voltages exceeding a predetermined minimum value.

A preferred embodiment of the invention includes a rectifier circuit and a D.-C. amplifier which includes inverse-feedback. Such a circuit provides a driving source of negligible impedance for the network described. Output is derived from the network from across the series resistor.

Among the objects of the invention are to provide a new and improved means for deriving a voltage of an amplitude which is a predetermined non-linear function of an applied voltage. Another object is to provide an improved means for deriving a voltage of an amplitude which is a predetermined function of a voltage applied to

2

a network which includes linear and non-linear impedance elements. A further object of the invention is to provide an improved means for deriving an output voltage the value of which is a predetermined function of a voltage applied to a network which includes a Thyrite element and one or more linear resistive elements. Still another purpose of the invention is to provide an improved means for applying voltages to non-linear networks which include a rectifier and substantially linear D.-C. amplifier to provide a driving source of negligible impedance.

The invention will be described in greater detail by reference to the accompanying drawing of which Fig. 1 is a schematic circuit diagram of a network including linear and non-linear impedance elements, Fig. 2 is a schematic circuit diagram of a preferred embodiment of the invention, and Fig. 3 is a set of explanatory curves relating to the operation of the apparatus of Fig. 2. Similar reference numerals are applied to similar elements throughout the drawing.

Referring to Fig. 1, a voltage E_1 is applied to the terminals 1, 2 of a network which includes a Thyrite or other non-linear element 5 which is connected in parallel with linear resistor R_s . One common terminal of the network R_s , 5 is connected to one terminal of a second resistor R_o . The remaining common terminal of the network R_s , 5 is connected to the input terminal 1. The remaining terminal of the second resistor R_o is connected to the remaining input terminal 2 and to one output terminal 4. The remaining output terminal 3 is connected to the common terminal of the network R_s , 5 and the second resistor R_o . The output voltage derived from the output terminals 3, 4 is designated as E_o .

Fig. 3 illustrates how the relation between E_o and E_1 varies with change in the values of R_s and R_o . In order to facilitate comparison of the different curves, the scale factor of E_o is adjusted so that the curves show the same maximum value of E_1 . It will be noted that the E_o vs. E_1 curve is steep when R_o is small and R_s is large. As R_s is lowered or R_o is increased, the average radius of curvature of the curve is increased in different ways. Thus increasing R_o increases the radius of curvature more at the top of the curve and decreasing R_s increases the radius of curvature more at the bottom of the curve. By using different ratios of R_s/R_o , the curve is made to change shape and still have the same average curvature. It is apparent, of course, that increasing R_o or decreasing R_s increases the output for a given input and so increases the scale factor.

The following table gives the results obtained with a given piece of Thyrite:

Slant Range	Time of Flight Sec. from Tables	Time of Flight Sec. from Thyrite Network
4300	8.85	8.85
4000	7.90	7.89
3500	6.43	6.41
3000	5.08	5.08
2500	3.90	3.90
2000	2.88	2.88
1500	1.99	1.99
1000	1.23	1.22
800	.57	.56
200	.22	.21
100	.11	.10

In securing this data, R_o was adjusted to 275 ohms and R_s was adjusted to 2000 ohms. The maximum input voltage corresponding to 4300 yards was 28.5 volts giving an input scale factor of about 151 yards per volt. The output for this same input was 8.5 volts giving an output scale factor of about 1.041 seconds per volt. It will be noted that the time of flight values indicated by the Thyrite network approximates very closely those taken from the tables.

Variation of the ratio R_s/R_o , as well as the magnitude of these linear resistive elements, permits a wide variety of network characteristics. It should be understood that the network described is merely typical of one embodiment of the invention and that other networks utilizing Thyrite, or other non-linear impedance elements, may be used to equal advantage for computing predetermined functions of quantities applied to the network as driving voltages. The values of the function are determined from a function table. R_s and R_o are experimentally adjusted by trial and error until the closest approximation to the desired function is obtained. Increasing R_s tends to make the function steeper throughout the curve. Increasing R_o tends to make the function less steep at the high voltage end. The higher the exponent of the "cell" of Thyrite, the lower R_s will be. Also R_o will need to be increased but not to the same degree that R_s is decreased. It is apparent that the scale factor of the function will change as R_s and R_o are changed.

Fig. 2 is a modification of the invention which includes means for providing driving voltages. A voltage E , which may, for example be an A.-C. potential of amplitude proportional to the particular selected value of the slant range of a ballistic equation, is applied to the input terminals 11, 12. The terminal 12 is grounded. Voltages applied to the input terminal 11 are impressed upon the cathode of a diode rectifier 13 through a coupling capacitor 14. A smoothing reactor 25 is connected between the filter 15 and the cathodes of the duodiode 13. The values of the capacitor 14 and the reactor 25 are not critical. The anode of the diode rectifier 13 is connected to the input of a conventional low pass filter 15. The output of the low pass filter 15 is applied to the control electrode of a first D.-C. amplifier tube 16 through a source of bias potential, such as a battery 17. The anode of the first D.-C. amplifier 16 is connected to the control electrode of a second D.-C. amplifier 17 which includes an anode voltage regulator device 18 such as an RCA-150 type tube in series with its cathode circuit. The second D.-C. amplifier 17 includes a degenerative cathode circuit comprising a series capacitor 19 and a series resistor 20

which are connected between the cathode current regulator 18 and ground. The voltage across this regulator functions as a simple bucking voltage to compensate for the positive plate voltage of the tube 17. Anode voltages are applied to the D.-C. amplifier tubes through conventional anode coupling resistors 21, 22. The second D.-C. amplifier 17 is cathode loaded to derive the voltage E_1 from across the degenerative network 19, 20. The voltage E_1 is applied to the terminals 1, 2 of the network of Fig. 1. The output voltage E_0 is derived from the terminals 3, 4 which are connected across the output resistor R_o . The output voltage E_0 may be indicated directly by a meter 23 connected across the output terminals 3, 4; or the voltages may be applied to other elements of a complete ballistics predictor, not shown. As explained heretofore, the value of E_0 will be a predetermined function of the value of E_1 depending upon the characteristics of the Thyrite element 5, and the relative magnitude of the resistors R_s and R_o . Since the rectifier-D.-C.-amplifier circuit just described is substantially linear in operation, the voltage E_0 will likewise be a predetermined function of the applied voltage E . The degenerative circuit of the D.-C. amplifier provides a coupling circuit of negligible impedance for the input terminals 1, 2 of the non-linear network. It is desirable that the impedance of the D.-C. amplifier, looking into the network input terminals 1, 2, shall be constant and lower than the resistor R_o . In general, the input impedance plus the tube impedance should be substantially equal to R_o .

It should be understood that the applied A.-C. potential E , having an amplitude proportional to a particular selected value of the slant range in a ballistics equation, may be derived in any manner known in the electronic predictor art. The extremely complex methods and apparatus for so deriving the voltage corresponding to the selected slant range form no part of the present invention. The instant device merely derives from the applied voltage a second voltage having a magnitude which is a predetermined function of the applied voltage. The particular function is determined by the known ballistics characteristics of a particular projectile. The function is then set up upon the instant device by adjusting the variable linear resistors R_s and R_o . It further should be understood that the adjustment of the resistors to the particular function may be accomplished by mathematical calculation or by experimental methods. The same procedure may be applied to many other mathematical problems requiring complex solution.

I claim as my invention:

1. Apparatus for computing electronically a predetermined non-linear function of a quantity including a source of voltage of amplitude proportional to the value of said quantity, linear means for deriving a D.-C. potential from said source, a network comprising a non-linear impedance element, a first linear impedance element connected in parallel with said non-linear impedance element, a second linear impedance element connected in series with said parallel-connected elements, and means for applying said D.-C. potential across said network, whereby a voltage corresponding to the value of said function of said quantity is produced across said second linear impedance element.
2. Apparatus of the type described in claim 1 including means for indicating directly the voltage across said second impedance element as a

2,428,596

5

measure of the desired value of said function of said quantity.

3. Apparatus of the type described in claim 1 characterized by the fact that the values of said impedance elements satisfy said function equation when the characteristics of the particular Thyrite element are represented by K and v in the equation

$$E_0 = KE;$$

where E_1 is the voltage applied to the network and E_0 is the voltage across the second impedance element.

4. Apparatus for computing electronically time of flight in a ballistics equation when the slant range is known, including a source of voltage of amplitude proportional to the slant range, linear means for deriving a D.-C. potential from said source, a network comprising a parallel connected Thyrite element and resistor in which one terminal of each is commonly connected to one terminal of a second resistor, and means for applying said D.-C. potential across said network, whereby a voltage corresponding to the value of said time of flight is produced across said second resistor.

5. Apparatus of the type described in claim 4

6

including means for indicating directly the voltage across said second resistor as a measure of the time of flight.

6. Apparatus of the type described in claim 4 characterized by the fact that the values of said resistors satisfy said ballistics equation when the characteristics of the particular Thyrite element are represented by K and v in the equation

$$E_0 = KE;$$

10 where E_1 is the voltage applied to the network and E_0 is the voltage across the second resistor.
